United States Patent Office

Des. 179,810
Patented Mar. 5, 1957

179,810

REAR VISION MIRROR

Frank N. Mariani, New York, N. Y.

Application June 1, 1956, Serial No. 41,740

Term of patent 14 years

(Cl. D14—6)

FIG.1

FIG.2

FIG.3

FIG.4

Fig. 1 is a side elevational view of the rear vision mirror, illustrating my new design.

Fig. 2 is a front view of Fig. 1.

Fig. 3 is a rear view of Fig. 1.

Fig. 4 is a plan view of Fig. 1.

The dominant features of my design reside in the portions shown in full lines.

I claim:

The ornamental design for a rear vision mirror, substantially as described and shown.
